 Baden, Switzerland

Application September 9, 1943, Serial No. 501,704
 In Switzerland May 29, 1942

2 Claims. (Cl. 315—189)

For the transmission of direct current power over long distances very high direct voltages are used for reasons of economy. These voltages are generally much higher than those which can be dealt with by single vapor discharge devices with a liquid cathode. It is therefore necessary to connect several such discharge vessels in series. One point of the direct current circuit is connected to earth and thus has earth potential. Both the adjoining vessels then behave in a normal manner as regards their voltage stress relative to earth and their control also presents no particular difficulty.

Each further discharge vessel connected in series with the first vessel is, however, at a higher potential than its predecessor. Not only does this demand a better insulation to earth but difficulties are also encountered as regards the control and auxiliary current circuits. The power for the auxiliary apparatus such as vacuum pump, ignition device, excitation and cooling installation, has to be supplied over special insulating transformers to the individual stages. Special devices are also necessary for the transmission of the variable control impulses to the grids of the discharge vessels operating either as controlled rectifiers or inverters. A mechanical displacement of the ignition point by means of a regulating and control apparatus which is at earth potential cannot meet the requirements. Especially when rapid control operations have to be undertaken such as a sudden change-over from rectifier to inverter operation in the case of short circuits on the direct current line, the delays caused by the acceleration of the moving masses are much too long. A further disadvantage of such a control system is the necessity of having to provide devices for each stage for the production of control voltages which are as far as possible rectangular in form. In order to increase the safety of the plant it is desirable that as much as possible of the entire control apparatus should be at earth potential. This is the only way by means of which sensitive parts can be easily supervised and repairs carried out without interrupting the transmission.

The present invention concerns a device for influencing the control grids by means of impulses and is characterised by the feature that the control impulses are produced with the shape and phase position necessary for control purposes in an apparatus which is at earth potential and are then supplied in the form of modulated high frequency currents to the grid circuits which are at high potential of the discharge vessel. By tun-

ing the high frequency circuits to the frequency of the carrier wave, the disturbing voltage peaks of power line frequency and its harmonics that during the commutation process in rectifiers and inverters, are withheld from the control circuits. The higher the carrier frequency relative to the maximum disturbing frequency which occurs, the more easily can the aforementioned advantage be obtained. A short wave is thus preferably selected for the carrier wave, this being a frequency range in which the radiation losses can still be readily controlled. For the transmission of the control impulses by means of high frequency a high frequency cable is used. 10

15 High frequency insulating transformers, which do not need to have an iron core, are used for coupling the cable to the high potential grid circuits. The high frequency impulses are then rectified and applied to the control grids as 20 direct current impulses in the original form.

A constructional example of the invention is illustrated diagrammatically in the accompanying drawing.

In the arrangement shown in the figure there 25 are two rectifier groups 1, 1' connected in series, which together with their control and auxiliary apparatus are at different high potentials relative to the earth. Each group consists of a double-anode discharge vessel operating in opposed 30 phases, the anodes 3, 3' being supplied from the associated transformer secondary windings 2, 2'. The control grids 4, 4' influence the arcs which burn to the cathodes 5, 5'. The cathodes which are conductively connected to the frameworks 35 1, 1' respectively which support all the apparatus belonging to one particular stage, and thus determine the potential of these frameworks relative to the earth. Of all the auxiliary apparatus which is screened off to protect it against disturbing voltages, only the control circuits for the 40 grids 4, 4' are indicated in the drawing. Control voltages are applied to these grids over resistances 6, 6' and grid condensers 7, 7'. As regards the present invention, it is immaterial 45 what form the control voltages have. Generally, however, rectangular impulses with a variable phase and as steep a flank as possible are employed. It is therefore important that the device for transmitting the control impulses from the regulating and protecting apparatus, which is at earth potential, to the grids should not detrimentally affect this steepness.

The impulses are transmitted at a high frequency, modulated in accordance with the impulses, over a screened cable, for instance con-

centric high frequency cables 13, 13', which connect the output transformers 14, 14' with the insulating transformers 8, 8'. The secondary windings are at a high potential and can be adjusted for maximum power reception by means of the condensers 10. The high frequency power is rectified by means of the rectifiers 9. Condensers 11 deal with the harmonics whilst the direct current impulses are supplied to the screened transformers 12, 12' which are constructed in such a manner that the impulses are transmitted as far as possible without distortion.

The impulses, which in this case control in opposite phases, are produced by means of the transmitting tubes 16, 16'. The anode direct current flows from the positive direct voltage terminal 20 over the oscillating coils 15, 15' to the anode and from thence to the cathode and over a resistance 21 to the negative terminal 22. Part of the oscillation power is fed back to one of the control grids of the tubes over the grid coils 18, 18' which are inductively coupled with the oscillating coils 15, 15', whereby these tubes can be caused to oscillate. The oscillation frequency depends largely on the natural frequency of the oscillation circuit formed by the coil 15 and the condenser 19. The working point of the tubes is thus determined by the negative grid bias voltage corresponding to the voltage drop of the anode current in resistance 21. The high frequency oscillations receive their impulse form as a result of their modulation by means of the further control grids connected to the terminals 17, 17'. The high frequency oscillations can be increased or entirely suppressed according to the bias voltage applied to these terminals. It is thus possible by controlling these grids to determine the phase, form and length of the high frequency control impulses as desired, by making them suit the bias voltage. The task of controlling the grids of the rectifiers which are at a high potential thus resolves itself into a low-voltage control of the grid voltage of the transmitting tubes, a problem which has already been solved and does not require any further explanation. In order to avoid mutual disturbances from an external source the oscillator circuits 24 are also mutually screened and decoupled.

For the invention it is unimportant what arrangement of connections is employed for generating the high frequency oscillations. Other means well known in the high frequency art can also be employed for this purpose. The invention can also be employed in connection with other converter arrangements, for instance with inverters. For reasons of uniformity the grids of all discharge vessels belonging to one and the

same power transmission plant are influenced in the same manner.

I claim:

1. A grid-controlled electron discharge device comprising a vessel having a liquid cathode therein, said vessel and cathode being at a high direct current potential with respect to ground, at least one control grid connected to said cathode through a control grid circuit, and biasing means for impressing control voltage impulses upon said control grid circuit; said biasing means including an electronic generator of high frequency oscillations, said generator having a ground potential connection and means upon which low frequency impulses may be impressed to modulate the generated oscillations, the frequency of said oscillations being in the short wave band and substantially higher than the frequencies of disturbing voltage surges resulting from the application to said control grid of control voltage pulses of the low frequency of modulation of said high frequency oscillations, a circuit at high potential with respect to ground and coupled to said generator, rectifier means in said coupled circuit to demodulate the modulated short-wave oscillations, thereby to develop low frequency voltage impulses, and means for transferring the developed low frequency voltage impulses to said control grid circuit.

2. A grid-controlled electron discharge device comprising a vessel having a liquid cathode therein, said vessel and cathode being at a high direct current potential with respect to ground, at least one control grid connected to said cathode through a control grid circuit, and biasing means for impressing control voltage impulses upon said control grid circuit; said biasing means including an electronic generator of high frequency oscillations, said generator having a ground potential connection and means upon which low frequency impulses may be impressed to modulate the generated oscillations, the frequency of said oscillations being in the short wave band and substantially higher than the frequencies of disturbing voltage surges resulting from the application to said control grid of control voltage pulses of the low frequency of modulation of said high frequency oscillations, a transmission circuit at high potential with respect to ground, means for impressing said modulated oscillations upon said transmission circuit, and means including a demodulator coupling said transmission circuit to said control grid circuit to impress thereon control voltage impulses corresponding to the low frequency modulation imposed upon the high frequency oscillatory output of said generator.

PAUL HUBACHER.
